US0D1059139S

(12) **United States Design Patent** (10) Patent No.: **US D1,059,139 S**
(45) Date of Patent: ** Jan. 28, 2025

(54) **COOKWARE UTENSIL**

(71) Applicant: **Lagom Kitchen Co.**, Los Angeles, CA (US)

(72) Inventors: **Amir Tehrani**, Los Angeles, CA (US); **Zachary Rosner**, Los Angeles, CA (US); **Melinda Olsen**, Los Angeles, CA (US); **Hlynur Atlason**, New York, NY (US); **Christopher Santone**, Brooklyn, NY (US)

(73) Assignee: **Lagom Kitchen Co.**, Los Angeles, CA (US)

(**) Term: **15 Years**

(21) Appl. No.: **29/826,404**

(22) Filed: **Feb. 11, 2022**

Related U.S. Application Data

(60) Continuation-in-part of application No. 29/800,806, filed on Jul. 23, 2021, now Pat. No. Des. 959,933, (Continued)

(57) **CLAIM**

The ornamental design for a cookware utensil as shown and described.

DESCRIPTION

FIG. 1 is a perspective view of a cookware utensil showing our new design;

FIG. 2 is a perspective view taken from the bottom thereof;

FIG. 3 is a right side elevation view thereof, the left side elevation view being a mirror image thereof;

FIG. 4 is a front elevation view thereof;

FIG. 5 is a rear elevation view thereof;

FIG. 6 is a top plan view thereof; and,

FIG. 7 is a bottom plan view thereof.

The broken lines are shown for the purpose of illustrating parts of the article that form no part of the claimed design.

1 Claim, 7 Drawing Sheets

Related U.S. Application Data

which is a division of application No. 29/748,445, filed on Aug. 28, 2020, now Pat. No. Des. 929,798, which is a continuation-in-part of application No. 29/699,401, filed on Jul. 25, 2019, now Pat. No. Des. 916,547.
